BICYCLE HANGER

Alexander L. Generalis, Michael C. Roberto, and David A. White, all of 249 S. 10th St., Philadelphia, Pa. 19107, and Dann S. Sheftelman, 4405 Pine St., Philadelphia, Pa. 19104

Filed Dec. 19, 1974, Ser. No. 534,633

Term of patent 14 years

Int. Cl. D8—99

U.S. Cl. D8—235

FIG. 1

FIG. 2

FIG. 3

FIG. 4

FIG. 6

FIG. 1 is a perspective view of a bicycle hanger showing our new design, it being understood that the broken lines are for illustrative purposes only.

FIG. 2 is a top plan view thereof.

FIG. 3 is a bottom plan view thereof.

FIG. 4 is a front elevational view thereof.

FIG. 5 is a rear elevational view thereof.

FIG. 6 is a side elevational view thereof, the other side being a mirror image of the side shown herein.

We claim:

The ornamental design for a bicycle hanger, as shown and described.
